(57) **CLAIM**

The ornamental design for a hanger for a folding panel system, as shown and described.

DESCRIPTION

FIG. 1 is an isometric view of a hanger for a folding panel system;

FIG. 2 is a front view of a hanger for a folding panel system;

FIG. 3 is a back view of a hanger for a folding panel system;

FIG. 4 is a left view of a hanger for a folding panel system;

FIG. 5 is a right view of a hanger for a folding panel system;

FIG. 6 is a top view of a hanger for a folding panel system; and,

FIG. 7 is a bottom view of a hanger for a folding panel system.

1 Claim, 7 Drawing Sheets
